United States Patent Office

Des. 206,028

Patented Oct. 18, 1966

206,028

COMBINED JAR AND COVER THEREFOR

Charley F. Bartlett, Sapulpa, Okla., assignor to Bartlett-Collins Company, Sapulpa, Okla., a corporation of Oklahoma

Filed Nov. 1, 1965, Ser. No. 87,957

Term of patent 14 years

(Cl. D58—25)

Fig. 1

Fig. 2

Fig. 3

I claim:

The ornamental design for a combined jar and cover therefor, as shown.
